UNITED STATES PATENT OFFICE.

JAMES WILLIAM LESLIE, OF EVERETT, MASSACHUSETTS.

AUTOMATIC RAILWAY-SWITCH.

SPECIFICATION forming part of Letters Patent No. 398,169, dated February 19, 1889.

Application filed November 1, 1888. Serial No. 289,743. (No model.)

To all whom it may concern:

Be it known that I, JAMES WILLIAM LESLIE, of Everett, county of Middlesex, State of Massachusetts, have invented an Improvement in Automatic Railway-Switches, of which the following description, in connection with the accompanying drawings, is a specification, like letters on the drawings representing like parts.

10 This invention has for its object to construct a switch for railway-tracks which is operable by means of a device located upon a car, the invention being especially applicable for street-railways, and the operating device located upon or carried by the car being operated by the driver.

In accordance with this invention the switch or tongue is secured to a stud which is partially rotated or turned in one or the other 20 direction by rods or bars which are moved longitudinally by bell-crank levers turned on their pivots by the simultaneous action of the wheel of the car and of the device controlled by the driver.

25 The invention consists in details of construction to be hereinafter pointed out.

Figure 1 shows in plan view a small sectional track having a switch constructed in accordance with this invention; Fig. 2, a longitudinal section of the track, taken on the dotted line, Fig. 1, and also a sectional view of a portion of a car provided with a device operable by the driver; Figs. 3 and 4, details to be referred to, and Fig. 5 a modification to 35 be referred to.

The rails *a* and the switch or tongue *b* are all as usual. The switch or tongue is fastened to a stud, *b'*, which passes vertically through the material of the rail and into the 40 bed or foundation, it being understood that the foundation is recessed to receive the operating parts. A plate or bar, *c*, is secured to the stud *b'* within the recess or chamber in the bed or foundation, said plate or bar having loosely connected with it rods or bars *d'*, extending horizontally in opposite directions. The rod or bar *d'* is loosely connected 45 at its opposite end with one arm, as 2, of a bell-crank lever pivoted at 3, the other arm, 50 4, of the said lever being recessed near its outer end. A cross-bar, 5, passes through the recess formed in the arm 4 of the bell-

crank lever, it being held in position by a pin, 6, the recess being much larger than the cross-sectional area of the bar, so that the bar 55 may rock on or with the pin 6 freely.

The cross-bar 5 has loosely connected with it at each end a vertical stud, as 7 8, rising through apertures formed in the rail, one of the studs, as 7, occupying a position to be 60 acted upon by the tread-face of the car-wheel, and the other stud, as 8, occupying a position remote therefrom, so as not to be acted upon by the car-wheel.

A bell-crank lever is pivotally connected to 65 a bracket or frame beneath the car, to one arm of which, as *f*, a roller, *f'*, is attached, the other arm, as *f*², being connected by a connecting-rod, *f*¹, with one arm, as *f*³, of another bell-crank lever pivoted to a bracket or frame, 70 *f*⁵, the other arm of said last-named bell-crank lever being loosely connected with a vertical rod which passes vertically through the platform of the car and is provided at its upper end with a rest or foot-plate to be acted 75 upon by the foot of the driver.

As a car is passing along, the tread-face of the wheel depresses the stud 7, and thereby turns the cross-bar 5 on its pivot, but otherwise effecting no result; but, if desired to 80 turn the switch, the roller *f'* is depressed, as herein shown, by the foot of the driver, and it, acting upon the stud 8 simultaneously with the action of the tread-face of the wheel upon the stud 7, depresses the cross-bar 5 and 85 moves the bell-crank lever, to thereby move the rod or bar *d'* longitudinally, swinging the plate or bar *c* and turning the switch or tongue.

The rod or bar *d* is connected with the bell- 90 crank lever at the opposite side of the switch and is arranged and adapted to be operated in substantially the same manner as the bell-crank lever 2 4; so a detail description need not be given further than to say that in operation the rod *d* is moved in a direction opposite to the movement of the rod *d'*, and hence 95 serves to restore the switch when set by the rod *d'*.

By employing two studs, as 7 8, located as 100 shown and described, it will be observed that the switch cannot be operated by a passing vehicle.

In Fig. 5 the arm 4 of the bell-crank lever

passes through a block, *o*, which moves freely on said arm, and the cross-bar *5* is supported by the block *o*. By this construction a more durable bearing is obtained for the cross-bar *5*.

I claim—

1. The switch or tongue and the longitudinally movable rods *d d'* for moving it in opposite directions, combined with two vertically movable studs for each rod *d d'*, pivotally arranged cross-bars connected with the said rods and to which the studs are connected, the roller *f'*, and means, substantially as described, for effecting its movement, all substantially as and for the purposes specified.

2. The switch or tongue, the longitudinally movable rods *d d'*, and the pivoted cross-bars *5*, connected with the rods or bars *d d'*, com-

bined with the studs downwardly movable independently or simultaneously, substantially as described.

3. The switch or tongue, the longitudinally movable rods *d d'*, the bell-crank levers and pivoted cross-bars, and the independently or simultaneously movable studs, combined with the roller *f'* and means for moving it to operate with the ear-wheel to effect the simultaneous movement of the studs, substantially as described.

In testimony whereof I have signed my name to this specification in the presence of two subscribing witnesses.

JAMES WILLIAM LESLIE.
